WINDOW SCREEN

Joseph Sylvan, Berkley, Mich.

Application June 18, 1945, Serial No. 600,019

7 Claims. (Cl. 160—375)

1

This invention relates to improvements in window screens.

An object is to provide a window screen having a metal frame which frame is particularly adapted to be easily and quickly adjusted to fit window openings of slightly different size.

Another object is to provide a window screen having a metal frame provided with one or more window jamb engaging strips which strips are adapted to be adjusted relative to the frame to make the screen frame fit the window opening. More particularly the metal frame exhibits outwardly open folds or channels extending along certain margins and the adjustable marginal jamb engaging strip is frictionally adjustably received within such outwardly open fold or channel formed in the metal frame. The strip is resistingly adjustable inwardly or outwardly within the channel to increase or diminish a dimension of the screen frame.

A meritorious feature is that this adjustable marginal strip is not only adjustable within the channel relative to the screen frame member but the strip includes an outer marginal flange which is bendable to vary the overall dimension of the screen frame.

Another object is to provide a screen having a metal frame wherein the frame parts, the end frame members and the top and bottom frame members, are so constructed and interlocked together at the ends and without the use of auxiliary fastening means as to provide a simple, rigid, light weight and inexpensive screen structure.

Other objects, advantages and meritorious features will more fully appear from the following description, appended claims and accompanying drawing, wherein:

Figure 1 is a front elevation of a screen structure embodying this invention.

Figure 2 is a horizontal sectional view taken on the line 2—2 of Figure 1.

Figure 3 is a vertical sectional view taken on the line 3—3 of Figure 1.

Figure 4 is a perspective of a corner fragment of a screen frame showing an adjustable jamb strip in position.

Figure 5 is a perspective of a corner fragment of a screen frame showing the adjustment strip separated therefrom.

Figure 6 is a rear elevation of a corner fragment of this screen.

This screen structure represents an improvement upon or modification of the screen structure illustrated in my pending patent application Serial No. 592,339, filed May 7, 1945.

The screen mesh wire is indicated as 10. It is cut over size the opening defined by the screen frame and is folded along each margin, as at 12, over an angular flange 14 of the screen frame. It

is stretched taut across the frame opening and securely held upon said flange 14 by a channel retaining strip 16 as described in the patent application above referred to.

The screen frame illustrated comprises a top frame member 20, a bottom frame member 22 and two end frame members 24. Each of these frame members is provided with its flange 14 and a channel retaining strip 16 is provided for the flange of each frame member. These flanges collectively form a substantially continuous flange about the frame opening. These channel retaining strips are pinched tightly upon the screen wire 10 holding the wire against the flanges 14 over which they are received as shown in Figures 1 and 3. These channel retaining strips are interlocked together at the corners as shown in Figures 1 and 5 by having end laps or extensions 18 folded over each other as shown in the drawing.

The top and bottom frame members 20 and 22 respectively are folded over inwardly as at 26 as shown particularly in Figure 3. The inner margin of the top frame member 20 is bent upwardly at an acute angle to the plane of the frame member to form the upper flange 14 heretofore referred to. The inner margin of the bottom frame member 22 is bent downwardly upon itself at an acute angle to the plane of the frame member to form corresponding bottom flange 14 heretofore referred to. The ply 26 of the top frame member projects at each end as at 29 beyond the ply 20 of such member and the ply 26 of the bottom frame member projects at each end as at 29 beyond the ply 22 of such member.

Each end frame member 24 is folded over along its inner margin outwardly upon itself as at 30 forming an outwardly open channel. This outwardly extending fold 30 is also bent along its outer margin as shown in Figure 2 to form the end retaining flange 14 for the screen wire. The outer margin of each end frame member 24 is folded over inwardly upon the frame member as at 32. This fold 32 laps over the projecting ends 29 of the top and bottom frame members 20 and 22 respectively as shown in Figures 2, 4, 5 and 6 thereby securing the end frame members 24 and the top and bottom frame members 20 and 22 together to form a complete rugged screen frame structure.

The outwardly open channel in each end frame member 24 formed by the fold 30 is adapted to snugly frictionally adjustably receive an angular jamb engaging adjustment strip 34 as shown. Each adjustment strip 34 is provided with an angular channel fold 36. The outer wall 37 of this channel fold 36 is adapted to fit snugly against an end jamb within the window opening. The strip 34 may be withdrawn outwardly relative to the end member 24 or pro-

jected inwardly relative thereto to accommodate the screen frame to window openings of different size.

To further facilitate the engagement of the ends of the screen with the side jambs of the window opening and to accommodate the screen frame to window openings of different size the channel flange 36 may be spread apart or closed together. If desired the channel flange 36 may be bent as a unit relative to the plane of the member 34 in which event the outer wall 37 of the channel 36 will lie flat against the side jamb of the window opening at different positions of adjustment. On the other hand the side wall 37 may be bent outwardly angularly to increase the overall dimension of the screen.

The adjustment strip 34 may be disposed within the open channel of the end frame member 24 in such a manner that the flange 36 may project either toward the front face or toward the rear face of the screen unit whichever may be desired for purposes of engagement with or securement to the window screen opening in a wall.

What I claim is:

1. A sash frame defining an opening and adapted to be received within a window opening, said sash frame including a sash member formed of a metal strip folded outwardly upon itself from the inner margin of the sash opening forming an outwardly open channel fold, the walls of which are held yieldingly toward each other, a marginal adjustment strip extending lengthwise along said sash frame and received within said channel fold frictionally grippingly engaged thereby and resistingly adjustable to different positions of withdrawal with respect thereto.

2. A window unit adapted to be received within a window opening comprising a sash frame defining an opening, said sash including a sash frame member formed of a metal strip folded outwardly upon itself from the margin of the sash opening forming an outwardly open channel fold, the walls of which are held yieldingly toward each other, a marginal adjustment strip extending lengthwise along said sash frame member and received within said channel fold frictionally grippingly engaged thereby and resistingly adjustable to different positions of withdrawal with respect thereto, said adjustment strip having an angular marginal flange and being removable from the channel fold and replaceable therein to reverse the direction of the flange.

3. In a sash structure a sash frame member formed of sheet metal folded upon itself forming a channel the entrance to which extends linearly along the outer margin of the frame member and a jamb engaging strip extending linearly along and received within said channel and being adjustable within the channel to different positions of relative withdrawal with respect thereto.

4. In a sash structure a sash frame member formed of sheet metal folded upon itself forming a channel the entrance to which extends linearly

along the outer margin of the frame and a jamb engaging strip extending linearly along and received within said channel and being adjustable within the channel to different positions of relative withdrawal with respect thereto, said strip having a deformable channel shaped flange extending along its outer margin and projecting angularly with respect to the plane of the strip.

5. A screen sash having a frame member formed of sheet metal and folded upon itself forming a channel opening outwardly along the outer margin of the frame, a jamb engaging strip frictionally adjustably receivable within said channel and extending lengthwise thereof, said strip having an angular flange extending along its outer margin substantially normal to the plane of the strip.

6. A screen sash having a frame member formed of sheet metal folded lengthwise upon itself forming a channel which opens outwardly along the outer margin of the frame member, a jamb engaging strip frictionally adjustably received within said channel and extending lengthwise thereof and projecting outwardly therebeyond, said strip having an angular flange extending along its outer margin substantially normal to the plane of the strip, said flange being swingable along a line extending lengthwise of the strip to vary the projection of the outer margin of the flange beyond the outer margin of the frame member.

7. A window screen comprising a sash frame defining an opening, said sash formed of a metal strip folded outwardly upon itself from the margin of the sash opening forming an outwardly open channel fold, the walls of which are held yieldingly toward each other, screen wire mesh extending across the opening in the sash and secured thereto, a marginal adjustment strip extending along the frame received within said channel fold and frictionally grippingly engaged therein, said strip being resistingly adjustable to different positions of withdrawal with respect thereto, said adjustment strip having an angular marginal flange and being removable from the channel fold and replaceable therein to reverse the direction of projection of the flange, the flange of said strip being folded lengthwise upon itself.
